INSECTICIDE VAPORIZER

Charles F. Holbrook, Harlingen, Tex.

Application July 13, 1953, Serial No. 25,902

Term of patent 7 years

(Cl. D31—3)

To all whom it may concern:

Be it known that I, Charles F. Holbrook, a citizen of the United States, and resident of Harlingen, Texas, have invented a new, original, and ornamental Design for Insecticide Vaporizer, of which the following is a specification, reference being had to the accompanying drawings, forming a part thereof.

Figure 1 is a perspective view of an insecticide vaporizer, embodying my new design.

Figure 2 is a top plan view of the vaporizer,

Figure 3 is a side elevation of the same,

Figure 4 is a central vertical section taken on line 4—4 of Figure 2, and,

Figure 5 is a horizontal cross section taken on line 5—5 of Figure 4.

I claim:

The ornamental design for an insecticide vaporizer, as shown.

CHARLES F. HOLBROOK.
